Samuel Thomson.

Letters Patent. Granted. (May 6th 1836.)

The Schedule referred to in this Letters Patent, and making part of the same, containing a description in the words of the said Samuel Thomson himself of his Improvement in the System of Botanic Practice of Medicine.

Be it known that, S. Samuel Thomson, of Boston, in the County of Suffolk and State of Massachusetts, have made certain new and useful discoveries in preparing medicines and in the mode of administering the same, to cure diseases, called "Thomson's Improved System of Botanic Practice of Medicine"; which is described as follows. - First. The mode of preparing an emetic, in all cases where the same is necessary; - that is to say in all forms of disease caused by cold, or obstructed perspiration. Take of the leaves of Lobelia Inflata, of Linus, pulverized to a fine powder, (one fine to twenty grain in warm water sweetened) - or in a tea of red raspberry leaves; or in any tea powder for removing cunker; the dose is to be repeated until the desired effect ^{shake} be produced. This preparation is for the less violent attacks of disease in adults; or for children. - Second. Take of the root of the Lobelia, referred to, one pound, finely pulverized, with one pound of white sugar, the whole to be well pounded together. - the sugar being designed to absorb the oil; - then add, half a pound of the best saffron; - quarter of a pound of mace powder; one gallon of improved rhumatic drops as hereinafter described: - Now, two drachms full for an adult, in a gill of Myrtle root bark tea, sweetened; - or in a strong decoction of the following compound; namely, 3 lbs of Myrtle root bark, 1lb 5 golden seal, 1lb ginger, 2oz Capriano, 2oz cloves, all pulverized fine and sifted through a fine sieve and well mixed together. For a dose take a drachmful in hot water, sweetened; half this quantity for children, and more or less according to age. This also may be used for the less violent attacks of disease to be taken warm. - The Schedule.

being in bed with a hot brick or stones wrapped in several thicknesses of cloth with water of vinegar, placed at the feet. It may be here observed that, steaming by the Inventor's plan is of the utmost importance in this mode of practice. Injections are also of the utmost importance to remove cancers below the neck of medicine given in the usual way. The directions to prepare and use the same with steam are to be found in my "Guide to Health" secured by copyright. Mode of relaxing the muscles in setting a bone; is in Midwifery. Relax the muscles in setting a bone if the patient be in bed, or shielded from cold air by a blanket, near the fire; administer a dose of the compound bark, named; If this does not produce a perspiration, give a dose of the second preparation of the Colic and wrap up the part affected with cloths next with soot as warm as can be borne; and pour hot water upon the part until the muscles relax sufficiently. In this way a bone may be set with your thumb and finger, and with very little trouble to the operator, or pain to the Patient, which by the common method it would require from two to six men causing the most excruciating pain to the Patient. The same method may be resorted to in midwifery, or child bed delivery, by taking the medicine as advised and near the time of delivery let the Patient drink freely of Infusing leaf tea with a portion of Cosmetic number two Capaicum (see my "Guide to Health") which will hasten or delay the delivery as nature requires. - Then put several diapers or cloths in a kettle of hot water and have every thing ready that no time may be lost, when the pain is approaching, apply a cloth as hot as can be borne to slack the muscles before described which will abate the pain; as soon as the pain relieves change the cloth for another hot one; this will perform that which nature, or the pain, are striving to accomplish; and by this mode at least three fourths of the strength of the suffering patient can be preserved, as much required at this critical period. By maintaining the perspiration after delivery the alarming complaints incident in such cases will be prevented. - the Patient will be convalesced to her strength and vigor. In this way the husband can attend to his wife, and she to her

right hand until experience shall proclude the necessity of poison.

Anti-Dyspeptic Conserve Preparation. — Take one pound of the fresh blossoms of Hollyhock, or of the dry ones reduced to the same consistence of the green, pound them well together in a mortar; — then add 1 lb. of White Sugar — pound until a paste is formed; — then knead or work in with a pestle the following powder made fine; namely, — 3 lbs. of Poplar bark, 1/2 lb. of Golden Seal, 1/2 lb. of Hollyhock (blossoms), 1/2 lb. of Cloves, — 2 lbs. of Ginger. — 1/2 lb. of Sassafras bark, — 1/2 lb. of Capsicum; when it becomes of the consistence of dough then add 100 grains of oil of pennyroyal well mixed; this form it into a loaf to dry; or form it into pills. A piece of the conserve in the pocket, and used as a substitute for tobacco, which may be substituted with the saliva instead of spilling it off as in the use of hats, pillows, pipes, tobacco; — the former will invigorate whilst the latter will debilitate the system; — it will make persons fleshy and strong; instead of lean and weak; it is a powerful antidyspeptic agent; — it may be carried in a box or paper and used instead of tobacco. The spring is the best time to try the ^{benefit} effects of this medicine when the weather is becoming warm; — persons faint — the digestion poor, and the body cold, for want of food and digestion power to consume it. When this medicine is used the dyspepsia will cease, because the food is digested or consumed like the fire in the grate, which keeps up that heat on which the fire in the grate, and the life in the body depends; this is the cause of consumption, and thus the cure for it.

Anti-Dyspeptic Balsamic. — Take of the bark of the quaking asp 3 lbs. of Golden Seal 3 lbs. of Run herb 1 lb. Juniper 1 lb. cloves 1 lb. Mace 1 lb. cinnamon 1 lb. ginger 3 lbs. capsicum 1 lb. & 13 lbs. of white sugar, all made fine and well mixed together and put up for use. Boil 10 lbs. powder to 1 quart of hot water, or a teaspful in a tumbler of hot water, sweetened; this is the best mode of using it. For some bitters not out of the powder in a common junk bottle scalded in 1/2 pint hot water; then fill the bottle with the best sweet malaga wine & sugar at discretion. — A syrup for relieves summer complaints. Take one pound of Poplar bark; 1 lb. of Mad dog bark of the green root; 1 lb. of Bayberry; 1/2 pound Golden Seal; 1/2 lbs.

hops - boil and strain off eight gallons, - then add 35 lbs white sugar scalded; skivvils, then add 1 lb cloves when hot and put it in a keg. Then cool add two gallons improved rheumatic syrup. Rose for an adult from 16 to 20 wine glass full and repeat at discretion till cured. - Improved Rheumatic Syrup. Take of quon myrrh 1 lb; of Spleen bark 1 lb of Thyme 1 lb; Capricorn 1 oz, the whole to be put in one gallon of strong high wine or high proof brandy and let it be well shaken together. dose from one to 2 tea spoonfuls.

What I claim as my discoveries and which I desire to secure by Letters Patent, are the before described modes of preparing and administering the above medicines for the purposes herein named.

Witnesses.
